CHARLES L. GOODRUM, OF NEW YORK, N. Y., ASSIGNOR, BY MESNE ASSIGNMENTS, TO WESTERN ELECTRIC COMPANY, INCORPORATED, A CORPORATION OF NEW YORK.

CALL-REGISTERING SYSTEM FOR AUTOMATIC TELEPHONE SYSTEMS.

1,193,137.

Specification of Letters Patent.

Patented Aug. 1, 1916.

Application filed April 24, 1915. Serial No. 23,565.

To all whom it may concern:

Be it known that I, CHARLES L. GOODRUM, a citizen of the United States, residing at New York, in the county of New York and State of New York, have invented certain new and useful Improvements in Call-Registering Systems for Automatic Telephone Systems, of which the following is a full, clear, concise, and exact description.

10 This invention relates to telephone exchange systems employing automatic line finder switches for associating calling lines with idle connecting circuits. Its object is to provide an improved metering circuit 15 arrangement for such systems.

In accordance with this invention the operating magnet of the meter of each line is connected to the multiple test contacts of such line in the automatic finder switches in 20 which such line appears and is of low resistance, and the test circuits of the finders are of high resistance relative to that of the meter magnets. With this arrangement the meters are not operated during the testing 25 operation of the finders, since the circuit conditions are such that their operating magnets will not receive enough current. When the calling line has been extended to a connecting circuit, however, and connection 30 has been made with the wanted line, the response of the called party renders operative means for closing a circuit of sufficient strength to operate the calling line meter magnet. The meter magnet is provided with 35 a locking winding so that upon its actuation it will remain locked up during the entire duration of the connection and thus prevent accidental operation of the meter. This locking winding may be included in part 40 allel with the cut-off relay of the line and may be controlled at an off-normal contact of the finder.

Referring to the drawings—Figures 1 and 2 show a circuit arrangement embodying the invention.

The subscribers' lines *a b* terminate as calling lines in multiple contacts 137, 138 of a group of finders like that shown diagrammatically in Fig. 1, and as called lines 50 in multiple contacts 225, 226 of a group of connectors like that shown diagrammatically in Fig. 2. The closure of the line circuit by the removal of the receiver from its switchhook by a calling party causes an idle 55 line finder to be set in motion to connect with

such line. The finder then in a primary rotary movement, selects the group of terminals containing the calling line and in a secondary vertical movement the particular line in such group which is calling. The 60 calling line is thus extended to the connector shown in Fig. 2 which is in turn caused to connect with the desired line by a primary and secondary movement under the control of the sender 157 of the calling party 65 at substation A.

A general description of the mode of operation having been given, it is thought the invention will be readily understood from a detailed description of the operation of interconnecting two substations.

The removal of the receiver 100 at substation A causes the closure of the line circuit and the operation of the line relay 108. Relay 108 at its armature and front contact 75 closes the circuit of relay 101 which is common to the group of subscribers to which substation A belongs. The relay 101 at its armature and front contact closes the following circuit for slow acting relay 105 to 80 start the line finder in motion: free pole of battery, relay 105, conductors 102, 111, finder off-normal contact 103, now closed to conductor 111, conductors 104, 109, armature and front contact of group relay 101, to 85 ground. A circuit for the side-switch escapement magnet 107 in parallel with relay 105 is also closed by relay 101 as follows: free pole of battery, left-hand winding of escapement magnet 107, conductors 90 110, 111, finder off-normal contact 103 to ground over the circuit just traced for relay 105. If the finder allotted to this group of lines is idle, a brush 115 carried by its wiper carrier or shaft (not shown) rests on a dead or home contact 116. In this position a set of wipers 128, 133, 136, 139 carried by the finder shaft is one step removed from operative relation to the group of line terminals containing those of substation A. 100 It is therefore necessary to give the finder shaft one rotary step before it can hunt over the terminals in the group to which it is allotted.

Upon the closure of the front contact of 105 slow relay 105, due to the energization of relay 101 as described, the following circuit is closed for the primary stepping magnet 118 of the line finder to give the finder this rotary step to pick out the group of lines 110

containing calling substation A: free pole of battery, primary stepping magnet 118, armature and back contact thereof, conductor 119, side-switch arm 120 and its first contact, 5 conductor 127, right-hand winding of escapement magnet 107, conductor 122, right-hand armature and front contact of slow-acting relay 105, conductor 123, conductor 200 (Fig. 2), left-hand armature and back 10 contact of relay 201, conductor 202, right-hand armature and back contact of relay 203, conductor 204, armature and back contact of relay 205 to ground. The primary stepping magnet 118 thereupon interrupts this circuit 15 at its front contact and a pawl carried thereby (not shown), rotates the finder brush shaft one step, whereupon the group test brush 115 engages the segment 158 of the group containing substation A, from which ground 20 was removed at the back contact of the group relay 101. Side-switch escapement magnet 107 releases the side or steering switch into its second position in the well-known manner, due to the opening of off- 25 normal contact 103. While the circuit of relay 105 is also opened when finder off-normal contact 103 opens, it is slow acting and before it can release its armatures the following circuit is closed through its right-hand armature and front contact free pole of battery, conductor 125, secondary stepping magnet 106, its armature and back contact, conductor 126, side-switch arm 120 and its second contact, conductor 127, right- 30 hand winding of side-switch escapement magnet 107, conductor 122, right-hand armature and front contact of slow relay 105, conductor 123, conductor 200 to ground at the back contact of relay 205 over the circuit 35 previously traced. The secondary stepping magnet 106, by means of a pawl (not shown) connected to its armature gives the shaft of the line finder a secondary vertical step due to the closure of this circuit, whereupon its 40 brushes 139, 136, 133, 128, engage with the first set of terminals of the group containing the terminals 138, 137, 132, 129 of calling line A. Contact between brush 128 and test terminal 129 occurs before the armature of 45 magnet 106 opens its back contact, this opening occurring near the end of its stroke. Escapement magnet 107 attracts its armature due to the closure of this circuit and locks itself up to ground at the armatures 50 and back contacts of the line relays 108 of non-calling lines over the following circuit: free pole of battery left-hand high resistance winding of escapement magnet 107, armature and front contact of said magnet, 55 conductor 112, side-switch arm 113 and its second contact, conductor 161, brush 128, terminals 129, low resistance right-hand windings of meter magnets 143, conductors 147, to ground at the armatures and back 60 contacts of line relays 108. This circuit is 65

closed before slow relay 105 releases. This relay is therefore maintained energized in parallel with escapement magnet 107. The secondary stepping magnet 106 now interrupts its circuit and causes the line finder 70 brushes to wipe over the terminals of the calling group. This circuit is as follows: free pole of battery, a conductor 125, magnet 106, its armature and back contact, conductor 126, side-switch arm 120 and its 75 second contact, conductor 127, right-hand winding of escapement magnet 107, conductor 122, right-hand armature and front contact of slow relay 105, conductor 123 to ground at the back contact of relay 205 of 80 the connector over the circuit previously traced. As soon as the calling line is reached, the escapement magnet 107 and slow relay 105 are deenergized, since no ground is present on the test terminal 129 85 thereof, due to the energization of the line relay 108. The escapement magnet 107 thereupon releases the side switch into position 3. The meter magnets 143 of the lines passed over during this testing operation do 90 not receive sufficient current to operate them, due to the high resistance of the right-hand winding of escapement magnet 107. When the side switch moves into position 3, cut-off relay 130 is immediately operated over 95 the following circuit: free pole of battery, relay 130, conductor 131, contact 132, brush 133, conductor 134, side-switch arm 113 and its third contact, conductor 112, armature and back contact of escapement magnet 107 100 to ground. The ground placed on brush 133 at the back contact of escapement magnet 107 causes this line to test busy in the connectors in which this line appears as will 105 hereinafter appear.

The cut-off relay 130 upon operating causes the deenergization of line relay 108 which, at its armature and back contact, restores this line to non-calling condition by grounding its multiple test contacts 129. As 110 the side switch moves into position 3, relay 205 at the connector is energized over the following circuit: free pole of battery, left-hand winding of relay 205, conductor 206, arm 207 and first contact of the connector 115 side-switch, conductor 132, polarized relay 133, side-switch arm 134 and its third contact, conductor 135, finder brush 136, contact 137, line conductor *b*, the telephone set of substation A, line conductor *a*, contact 120 138, finder brush 139, conductor 140, side-switch arm 141 and its third contact, conductor 142, conductor 208 side-switch arm 209 and its first contact, conductor 210, right-hand winding of relay 205 to ground. 125

The relay 133 is polarized so as not to operate by the closure of the circuit for relay 205 just traced. Relay 205, upon its energization, closes a circuit for slow acting relay 203 at its armature and front contact. 130

Relay 203, at its right-hand armature and front contact, prepares a circuit for the primary stepping magnet 227. The calling subscriber now operates his sender 157 and 5 interrupts the circuit of relay 205 a number of times, corresponding to the tens digit of the number of the called line. Each time the armature of relay 205 closes its back contact a circuit for primary stepping magnet 227 is closed as follows: free pole of 10 battery, magnet 227, side-switch arm 228, conductors 229, 212, right-hand armature and front contact of slow relay 203, conductor 204, armature and back contact of relay 15 205, to ground. The magnet 227 thus moves the wiper shaft in a primary direction by a pawl and ratchet (not shown), to pick out the group in the connector to which the called line belongs. Upon the 20 first break in the line circuit and the consequent falling back of the armature of relay 205, a circuit was closed for the side-switch escapement magnet 231 of the connector as follows: free pole of battery, 25 magnet 231, conductor 212, armature and front contact of relay 203, conductor 204, armature and back contact of relay 205 to ground. This magnet being slow-acting, remains energized until the closure of the 30 line circuit at the end of the tens series of breaks, whereupon it falls back and moves the side switch into position 2 in the well-known manner. Arm 228 thereof, in position 2 prepares a circuit for the secondary 35 magnet 232. Upon the operation of the sender 157 in transmitting the units digit of the wanted number, relay 205 is intermittently deenergized and the secondary stepping magnet 232 moves the connector 40 brushes to the terminals of the wanted line, the circuit being as follows: free pole of battery, magnet 232, side-switch arm 228 and its second contact, conductors 229, 212, right-hand armature and front contact of 45 slow relay 203, conductor 204, armature and back contact of relay 205, to ground, it being understood that slow acting relay 203 remains energized as during the first series of line circuit interruptions. Escapement 50 magnet 231 was energized upon the first closure of the back contact of the armature of relay 205 as during the tens selecting operation, and being slow-acting, releases only when the series of interruptions of the 55 line circuit corresponding to the units digit is over. It is then deenergized and moves the side switch into position 3. The selected line is immediately made to test busy in the connectors in which it appears by side-switch arm 233 grounding the multiple test contacts 234 thereof, and the cut-off relay 60 of the called line corresponding to relay 130 of Fig. 1 is operated.

In position 3, the arm 228 of the side switch closes a circuit for the escapement

magnet 231 to close the ringing circuit. This circuit is as follows: free pole of battery, magnet 231, conductor 229, arm 228 and its third contact, conductors 235, 217, armature and back contact of ringing control relay 218, to ground. The escapement magnet at its right-hand armature and front contact closes the ringing circuit as follows: free pole of ringing generator 236, ringing control relay 218, conductor 237, right-hand armature and front contact of escapement magnet 231, conductor 238, side switch arm 239 and its third contact, conductor 240, brush 241, terminal 226, line conductor a' , bell 242, line conductor b' , terminal 225, 70 brush 243, conductor 244, arm 245, conductor 246, conductor 224, armature and front contact of relay 205, to ground. When the called party answers, the marginal relay 218 is energized and opens the circuit of 75 the escapement magnet 231, whereupon the escapement magnet releases the side switch into position 4, thus opening the ringing circuit. Relay 201 is now energized and talking current is supplied to the 80 called line through the windings of this relay. It will be noted that when the side switch moves into position 4 upon the response of the called party, arms 207, 209 of the side switch reverse the connection of 85 the battery supplied to the calling party. The polarized relay 133 thereupon operates. 90 Upon the operation of polarized relay 133, it closes at its armature and front contact a circuit of sufficient strength to energize 100 the meter magnet 143. This circuit is as follows: free pole of battery (Fig. 1), primary stepping magnet 118, conductor 144, armature and front contact of polarized relay 133, conductors 145, 161, brush 128, contact 129, conductor 146, right-hand winding of meter magnet 143, conductor 147, right-hand armature and back contact of line relay 108 to ground. The operation 105 of magnet 118 has no effect at this time. The meter magnet thereupon attracts its armature 148. The armature of meter magnet 143 carries the stepping pawl 149 of the meter which, by advancing ratchet wheel 151 a step, records the connection which 110 has just been built up. Armature 148 at its front contact closes a locking circuit for the meter magnet as follows: free pole of battery, left-hand winding of the meter magnet 143, conductor 150, armature 148, 120 and front contact of the meter magnet, conductor 152, conductor 131, contact 132, brush 133, conductor 134, side switch arm 113 and its third contact, armature and back contact of escapement magnet 107 to 125 ground. Thus the meter remains locked until the connection is disestablished to prevent the accidental operation of the meter.

When the subscribers hang up their receivers upon the conclusion of the con- 130

versation, the relays 205 and 201 at the connector are deenergized. The following circuit for the release magnet 153 of the finder is thereupon closed: free pole of battery, 153, finder off-normal contact 154, conductor 155, right-hand armature and back contact of slow relay 105, conductor 123, conductor 200 (Fig. 2), left-hand armature and back contact of relay 201, conductor 202, right-hand armature and back contact of relay 203, conductor 204, armature and back contact of relay 205 to ground. In case the calling subscriber hangs up his receiver before the called subscriber, the release circuit is the same as that previously traced up to the left-hand armature of relay 201, and from thence passes by way of front contact of said armature, conductors 211 and 212, right-hand armature and front contact of relay 203, which is slow to release its armature, conductor 204, armature and back contact of relay 205 to ground. This impulse is sufficient to energize release magnet 153, which thereupon attracts its armature and locks itself up to ground through the finder off-normal contact 154 until the finder completely restores, whereupon it is deenergized by the opening of such off-normal contact.

When the called subscriber hangs up his receiver, the circuit for release magnet 213 of the connector is closed as follows: free pole of battery, left-hand winding of release magnet 213, conductor 214, right-hand armature and back contact of relay 201, conductor 215, side-switch arm 216 and its fourth contact, conductor 217, armature and back contact of the ringing control relay 218, to ground. The release magnet 213, upon its energization, restores the side switch to its normal position and closes a locking circuit for itself as follows: free pole of battery, left-hand winding of release magnet 213, conductor 214, right-hand armature and back contact of relay 201, conductor 215, side-switch arm 216 and its third, second or first contact, conductor 220, connector switch off-normal contact 221, conductor 222, left-hand armature and back contact of relay 203, conductor 223, conductor 247, left-hand armature and back contact of relay 201, conductor 202, right-hand armature and back contact of relay 203, conductor 204, armature and back contact of relay 205, to ground.

If the called subscriber hangs up his receiver before the calling subscriber the circuit previously traced for release magnet 213 through its left-hand winding to ground at the armature and back contact of ringing control relay 218 is closed whereupon the release magnet at its left-hand armature and front contact locks itself over the following circuit: free pole of battery, right-hand winding of release 213, its left-hand arm-

ture and front contact, conductors 219, 224, 248, to ground at the armature and front contact of relay 205.

In case the wanted line is busy as a called line its test terminal 234 is grounded by side-switch arm 233 of another connector; if busy as a calling line, said test terminal is grounded by side-switch arm 113 and armature and back contact of escapement magnet 107 of another finder. In this event, when under the control of the sender 157 of the calling party, the connector selects such busy line, the connector is immediately released and a busy signal is given to the calling party. It will be recalled that when the line circuit is permanently closed at the end of the last or units series of interruptions, the escapement magnet 231 of the side switch of the connector is deenergized and releases the side switch into position 3 to signal the selected line. Its left-hand armature is so arranged, however, that it closes its back contact before the side switch is released. The following circuit is then closed for release magnet 213 of the connector, if ground is present on test terminal 234 of the selected line, which will be the case if the line is busy as just explained: free pole of battery, left-hand winding of release magnet 213, conductor 214, right-hand armature and back contact of relay 201, conductor 215, side-switch arm 216 and its second contact, conductor 220, connector off-normal contact 221, conductor 222, left-hand armature and back contact of slow-acting escapement magnet 231, conductor 249, side-switch arm 233 and its second contact, conductor 250, brush 251, contact 234, to ground either at the side-switch arm 233 and its third or fourth contact of the connector connected to a multiple contact of this line, or at the back contact of the escapement magnet 107 of a finder connected to a multiple contact of this line. Thus the connector is released. The release magnet 213 at its left-hand armature and front contact locks itself over the following circuit: free pole of battery, right-hand locking winding, left-hand armature and front contact conductors 219, 224, 248, armature and front contact of relay 205 to ground. The release magnet 213 at its right-hand armature and front contact applies a busy tone over conductors 252, 253 to the calling line.

When the calling party hangs up his receiver, relay 205 is deenergized, opening at its armature and front contact the locking circuit of magnet 213, and at its back contact closing the following circuit to release the finder: ground, armature and back contact of relay 205, conductor 204, right-hand armature and back contact of relay 203, conductor 202, left-hand armature and back contact of relay 201, conductors 247, 200, 133

123, armature and back contact of relay 105, conductor 155, off-normal contact 154, release magnet 153 to free pole of battery. The release magnet locks itself up as previously described until the finder has reached its normal position, when by the opening of off-normal contact 154, it is released.

The finders are allotted to the calling lines by an extended starter wire. Each line group has a finder whose contact brush 115 normally rests on a home segment 116 of such group, adjacent a segment 158, also individual to such group. Thus, if a call comes in from any line in the group to which it is allotted, a single rotary step only of the brush shaft of the finder of such group is necessary to position its brushes to wipe over the terminals of such group as has just been shown. If the finder shown in Fig. 1 had been busy when the call just traced was initiated, the starter wire 104 would have been extended by finder off-normal contact 103, bottom, to the next idle finder, which would first be given a primary rotary movement by means of its primary stepping magnet corresponding to 118 of Fig. 1 to place such finder in a position to move its brushes over the terminals of the group containing the calling line. The starting circuit for such finder would then be as follows: ground, right-hand armature and front contact of group relay 101, conductors 109, 104, off-normal contact 103 bottom, conductor 180, armature and back contact of slow relay 105, conductor 159 to the primary magnet of the next idle finder. From this point the operation may be traced by reference to Fig. 1, and assuming the finder shown therein to be the idle one. The circuit then continues by conductors 160, 109, to escapement magnet 107 and slow relay 105, from which point the operation is the same as that already traced, except that the side-switch escapement magnet 107 of such finder would lock itself up to the grounded segments 158 of the non-calling line groups, and thus maintain the stepping circuit of the primary magnet 118 of such finder closed until the brush 115 thereof reaches the segment 158 of the calling line group from which ground is removed. Magnet 107 thereupon releases the side switch into position 2 to open the circuit of such primary stepping magnet and close the circuit of the secondary stepping magnet 106 of such finder to move the wipers over the calling group. From this point on, the operation is the same as that already described.

60 While in the present embodiment of the invention, the meter is operated upon the response of the called party, it is within the scope of the invention to operate the meter at some other stage in the process of building up or disestablishing the connection.

When the invention is applied to semi-automatic systems the polarized relay 133 may be under the control of the operator at the central office. For simplicity, no intermediate selectors have been shown. It is obvious however, that in actual practice a number of such selectors would be interposed between the finder shown in Fig. 1 and the connector of Fig. 2 depending upon the size of the exchange.

75 What is claimed is:

1. In a telephone exchange system, the combination with telephone lines, automatic finder switches wherein said lines terminate in multiple contacts, multiple test contacts for said lines in said finders, of meters connected with said test contacts and each provided with an operating winding of low resistance, a high resistance test circuit associated with each of said finders, 80 an operating circuit for said meter magnets associated with each of said finders, and means operated upon the response of the called party for closing said operating circuit to actuate the calling line meter. 85

90 2. In a telephone exchange system, the combination with telephone lines, automatic finder switches wherein said lines terminate in multiple contacts, multiple test contacts for said lines in said finders, of meters connected with said test contacts and each provided with an operating winding of low resistance, a test circuit associated with each of said finders including a test relay of relatively high resistance, an operating circuit 95 for said meter magnets associated with each of said finders, and means operated upon the response of the called party for closing said operating circuit to actuate the calling line meter. 100

105 3. In a telephone exchange system, the combination with telephone lines, means for interconnecting the same including automatic finder switches wherein said lines terminate in multiple contacts, multiple test terminals for said lines in said finders, of meters for said lines connected to said test terminals and provided with a double wound magnet having an operating winding of low resistance and a locking winding, a high 110 resistance test circuit for each of said finders, an operating circuit for said meter magnets associated with each of said finders, and means actuated upon the response of the called party for closing said operating circuit to actuate the calling line meter, whereupon said meter magnet locks itself up by means of its locking winding. 115

120 4. In a telephone exchange system, the combination with telephone lines, means for interconnecting the same including automatic finder switches wherein said lines terminate in multiple contacts, multiple test terminals for said lines in said finders, of meters for said lines connected to said test 125 130

- terminals and provided with an operating magnet of low resistance, a test circuit for each of said finders including a test relay of relatively high resistance, an operating circuit for said meter magnets associated with each of said finders and a polarized relay operated upon the response of the called party for closing said operating circuit to actuate the calling line meter.
- 5 5. In a telephone exchange system, the combination with telephone lines, means for interconnecting the same including automatic finder switches wherein said lines terminate in multiple contacts, multiple test terminals for said lines in said finders, of meters for said lines connected to said test terminals and provided with an operating magnet of low resistance, a test circuit for each of said finders including said meter magnet and a test relay of relatively high resistance, and an operating circuit for said meter magnets associated with each of said finders.
- 10 6. In a telephone exchange system, the combination with telephone lines, finder switches wherein said lines terminate, normally-grounded multiple test contacts for
- 15 said lines in said finders, a line relay for each line adapted when operated to remove ground from its multiple test contacts, steering switches for said finders, high resistance escapement magnets therefor, a test circuit for each finder including its escapement magnet, means for causing one of said finders to wipe over said test contacts and for energizing its escapement magnet upon the operation of any of said line relays, circuits for maintaining said magnet energized including grounded non-calling line test contacts, whereby when the test brush reaches the non-grounded calling line test contact said magnet is deenergized to move the associated steering switch to open the finder driving circuit, means operated by the stopping of the finder for replacing ground upon the calling line test terminals, a low resistance meter magnet for each line connected to its multiple test contacts, and means operated upon the response of the called party for closing an operating circuit for the calling line meter magnet.
- 20 25 In witness whereof, I hereunto subscribe my name this 21st day of April, A. D. 1915.

CHARLES L. GOODRUM.
